ABSTRACT

A fuse structure for an explosive device such as a hand grenade. The fuse structure has a detonator normally disposed in a noneffective safety position. A charge in the fuse structure is ignited when the grenade is released from the hand and is operable to release the detonator to effective position. The detonator carries a charge which is ignited only after the detonator has been released from ineffective position. The detonator charge will be operable for igniting a further charge which will detonate the explosive device only when the detonator is in effective position.

**PYROTECHNICAL FUSE WITH A DETONATOR
DISPLACEABLE FROM A SAFE POSITION INTO A
LIVE POSITION**

The present invention relates to a pyrotechnical fuse with a detonator displaceable from a safe position into a live position by driving force while being arrested in said safe position by a safety member.

In connection with fuses for projectiles it is known to arrest a detonator in its safe position by a pyrotechnically releasable safety member. After the projectile has been fired, the detonator is activated by burning off a pyrotechnical composition or set adapted to soften the safety member, whereupon the detonator is by a spring force moved into live position.

It is an object of the present invention to provide safety means for fuses equipped with pyrotechnical sets for hand grenades which will assure a maximum safety of operation.

It is another object of the present invention to provide a hand grenade equipped with a fuse, which during customary use will detonate only after the grenade has reliably left the position from which it has been thrown and after a certain time has passed.

It is still another object of this invention to provide a hand grenade as set forth in the preceding paragraphs, which is so designed that a premature detonation cannot be brought about due to a faulty manufacturing step.

These and other objects and advantages of the invention will appear more clearly from the following specification in connection with the accompanying drawings, in which:

FIG. 1 illustrates a longitudinal section through a time delay fuse according to the invention.

FIG. 2 shows on a larger scale than FIG. 1 a throttle valve and its adjacent part as used in the arrangement of FIG. 1.

FIG. 3 represents a modification of a fuse according to FIG. 1.

FIG. 4 is an isometric view of an embodiment which differs somewhat from that of FIG. 2.

FIG. 5 is a percussion fuse according to the invention and, more specifically, a longitudinal section therethrough.

FIG. 6 shows a modification of a portion of the fuse of FIG. 5.

The pyrotechnical fuse according to the present invention is characterized primarily in that a carrier for a detonator, which is connected to the stationary part of the fuse through the intervention of a pyrotechnically releasable safety member, is mounted in a tubular fuse housing having its lowermost part provided with a secondary charge and is axially displaceable therein and is adapted by a driving force to be moved with its detonator cap into the secondary charge where it is ignitable by a pyrotechnical composition or set as soon as the pyrotechnical set ignited by an igniter cap has released the safety member, said safety member being adapted to prevent an ignition of the detonator charge and of the secondary charge as long as the detonator carrier has not moved to its live position.

As safety member there may be employed a flap valve the flap of which in safety position is supported by an insulating disc and in live position is adapted to be bent open by the fire jet of the pyrotechnical set.

Within the range of the secondary charge, a cup-shaped insert may be provided for receiving the detonator cap while the bottom of the insert may have a conical recess at the side of the secondary charge which recess conveys the ignition shock from the detonator charge to the secondary charge only when the detonator cap is inserted into the insert. As a further safety measure, the detonator charge may be inserted into a tubular detonator cap which is produced or non-splintering material and the outlet cross-section of which at least equals the maximum inner transverse pipe section while the outer diameter corresponds to the inner diameter of the insert. Furthermore, between the ignition cap and the detonator there may be provided a throttle valve. Advantageously, the driving force may be produced by a helical pressure spring, and the pyrotechnically releasable safety member may be designed as a fusible member.

When a percussion fuse is involved, the stationary part of the fuse housing may have in a pendulum-like manner mounted therein a striker which is provided with an ignition passage. The said striker is in the safety position of the detonator fixed in radial and axial direction by the detonator carrier arrested by the safety member while the head portion of the striker is surrounded by a fuse composition which after displacement of the detonator carrier to its live position is adapted to ignite on the impact of the grenade by deviating the striker. By means of a rubber-elastic buffer located between the striker and the detonator carrier, a safe mounting of the fuse will be assured.

If the pyrotechnical set should prematurely be ignited, the ignition jet will rebound from the closed flap valve and, therefore, cannot ignite the detonator charge being in its safety position. The heat produced by the pyrotechnical set is kept away from the detonator charge by an insulating disc. Therefore, also an ignition of the detonator charge by overheating will be impossible. If the detonator charge will nevertheless be ignited while being in its safety position, the bottom of the cup-shaped insert will prevent the transfer of an ignition shock to the secondary charge inasmuch as the ignition shock effective at the insert bottom will be able to bend the bottom into the conical recess without affecting the secondary charge. The throttle valve will during the absence of a pyrotechnical set and during the absence of a flap valve prevent the ignition jet of the ignition cap from igniting the detonator charge.

With a percussion fuse equipped with a striker, a further safety step is realized by the fact that when a hand grenade has not been thrown far enough from its starting point so that its impact occurs before the striker has been released by the detonator, the grenade will after the expiration of a certain time be live but due to the failure of a further impulse of movement will not be detonated and thus will not endanger the soldier. On the other hand, the ignition of the activated detonator will be effected already at a small impulse of movement as it may be brought about when the grenade rolls off in response to a corresponding movement of the striker.

A detonator safety device consists in that the detonator after releasing the fuse cap will remain in safety position until after about two-thirds of the delaying time the meltable member is softened by the pyrotechnical set. Thus, the detonator is only then

moved by the helical spring into its live position. The ignition of the fuse cap can be effected only when the grenade has left the hand of the person throwing the grenade. By these safety devices it will be assured that the hand grenade can be thrown at any rate without endangering the respective soldier while on the other hand the enemy soldier will with a proper functioning of the fuse not have sufficient time to throw back the hand grenade.

Referring now to the drawings in detail, a tubular fuse housing 1 of a time delay fuse shown in its basic position in the drawing is screwed onto a head portion 2. Linked to the head portion 2 through the intervention of a bolt 3 is a yoke or the like 4 which is secured in its safety position by a safety pin or cotter pin or the like designated by reference numeral 5. Yoke 4 is on its inside engaged by a preloaded spring plate 6. An arm 7 with hammer 9 is through the intervention of a spring 8 pivotally arranged on the bolt 3. An ignition cap 10 is connected in an ignition cap carrier 11 which is positively connected to the upper end of a member 14 in the fuse housing 1. Between the ignition cap carrier 11 and a pyrotechnical delaying set 13 there is provided a chamber 12. The delaying set 13 is at the lower end of the member 14 (see FIG. 2) closed by a throttle valve 15 which has the shape of a cup and is provided with radially extending bores 16 and a flap valve 17. The flap valve 17 is connected by a unilateral flanging of the sleeve-shaped member 14.

A tubular detonator carrier 19 is approximately half-way placed over the member 14 and has its upper end connected to the member 14 by means of an annular melting member or fuse 18. Between a collar 14' of the member 14 and the end face 20 of the detonator carrier 19 there is provided a loaded helical pressure spring 21. At the lower end of the detonator carrier 19 there is screwed-in a detonator cap 22 with a detonator charge 23. A heat insulating disc 24 adapted to release the ignition passage 23' to the detonator charge 23 and preferably made of tetrafluorethylene is firmly mounted on the detonator cap 22 and engages the flap valve 17.

A carrier body 26 for a secondary charge 27 with positively connected cup-shaped insert 25 and a secondary charge 27 is screwed to the lower end of the fuse housing 1. Between the carrier body 26 and the detonator cap 22 there is provided an intermediate chamber 23''. The insert bottom 28 has a coaxially arranged conical recess 29. The secondary charge 27 is separated from the recess 29 and from the non-illustrated explosive charge of a hand grenade indicated in dot-dash lines by coaxial plates 30 and 31. Instead of the throttle valve 15 between the pyrotechnical set 13 and the detonator 22, it is possible for the same purpose and with an analogous effect to employ a disc 32 (FIG. 3) between the ignition cap 10 and the set 13. This disc 32 comprises an annular arrangement of a plurality of eccentrically arranged bores 33 and in the part 14 is connected to the wall of the chamber 12 upsetting.

A flap valve 34 illustrated in FIG. 4 comprises a circular disc which is folded at the part 14 and which comprises a hinge-like web 36 between the ends of an annular groove 35.

The percussion fuse illustrated in its basic position in FIG. 5 differs from the time delay fuse shown in FIGS. 1-4 merely as to the following details.

In a part 37 there are provided two chambers 12 and 38 which are separated from each other. A pyrotechnical set 39 for the fusible member 18 is arranged in the upper chamber 12 whereas a head portion 41 with ignition set 40 pertaining to a striker equipped with an ignition passage 42 extends into the lower chamber 38. The striker 43 is mounted in a pendulum-like manner in a disc 44 which is connected to the lower end of part 37. The foot portion 45 of the striker 43 is positively arranged in a recess 46 of the detonator carrier 19 while at the bottom of the recess there is provided a rubber-elastic buffer 47. The lower opening of the ignition passage is closed by the flap valve 17. A cup-shaped ignition set 48 shown in FIG. 6 is connected to a sleeve 49 in the lower chamber 38. The head portion 50 extends in a contact-free manner into the ignition set 48. The effect of this arrangement is analogous to that described in connection with FIG. 5.

Function of the time relay fuse of FIG. 1.

When the safety pin 5 has been removed, the yoke 4 is by means of the spring plate 6 and by the preloaded spring 8 pivoted in counter-clockwise direction while eventually yoke 4 and plate 6 are thrown off from the head portion 2. Subsequently, the hammer 9 hits the fuse cap 10 as a result of which the pyrotechnical delaying set 13 is ignited. The heat produced by the delaying set 13 softens up the fuse 18 so that the helical spring 21 will be able to press the detonator carrier 19 downwardly into its live position. In this position, the detonator cap 22 with its lower opening will be located at the insert bottom 28. Only at the end of the burning of the delaying set 13, the flap valve 17 is by a fire jet bent open which will then through the ignition passage 23 hit the detonator charge 23. This initiating shock of the detonator charge 23 impacts directly upon the insert bottom 28 and ignites the secondary charge 27 which initiates the detonation of the hand grenade. If the working of the fuse is irregular, the following actions of the safety devices will take place.

When the detonator carrier 19 is in its safe position, it will be appreciated that at a premature ignition of the delaying set 13, the flap valve 17 will prevent the fire jet from igniting the detonator charge 23. The valve 17 cannot be bent open because of the adjacent heat insulating disc 24. An ignition of the detonator charge 23 can, therefore, not be realized by bending open the flap valve 17 nor by a heat flow.

If the delaying set 13 and the flap valve 17 are missing, an ignition of the detonator charge 23 in its safe position is prevented by the throttle valve 15. The fire jet of the fuse cap 10 will impact upon the throttle valve 15 while only a minor portion of the ignition jet energy passes through the lateral bores 16 into the adjacent hollow chamber where it is subjected to turbulence. This minor portion of the ignition jet is insufficient for igniting the detonator charge 23.

If it has been overlooked to insert the delaying set 13, the flap valve 17 and the throttle valve 15, and if therefore the detonator charge 23 is ignited in its safety position, the initiating shock of the detonator charge 23 will spread to all sides in the intermediate chamber 23''. In this way, the said shock softens to such an extent that

the initiating pressure which is still effective at the insert bottom 28 will be absorbed by said insert bottom. The insert bottom 28 easily bends into the recess 29 without affecting the secondary charge 27.

If finally the delaying set 13 is missing, and the detonator carrier 19 would at a time when the fuse cap 10 is released occupy its live position, the fire jet of the ignition cap will by the throttle valve 15 be weakened to such an extent that the fire jet cannot bend open the flap valve 17 and cause ignition of the detonator charge 23. Even if the flap valve 17 would be lacking, the energy of the throttled ignition jet would not be sufficient to ignite the detonator charge 23. If the fuse has been correctly manufactured and if the ignition process takes its normal course, the described effect of the respectively built-in throttle valves 15 and 32 will not take place.

Function of the percussion fuse of FIG. 5.

After the pyrotechnical heating set 39 has been ignited which in view of the developed heat softens the fuse member 18, the helical spring 21 will press the detonator carrier 19 into its live position. The detonator carrier 19 will release the striker 43 which was previously arrested in the recess 46 of the detonator carrier 19 in radial and axial direction, and the flap valve 17 is released. If now the fuse receives a shock, the head part 41 with ignition set 40 impacts upon the wall of the chamber 38. The ignition jet of the ignition set 40 extends through the ignition passage 42 of the striker 43 and bends the flap valve 17 open so that the ignition jet can unimpededly hit the detonator charge 23 which is in live position and can ignite the same. The ignited detonator charge 23 will then ignite the secondary set 27 and this will initiate the detonation of the hand grenade.

If the detonator charge 23 accidentally ignites in safety position of the detonator carrier 19 while the flap valve 17 is missing, it will be appreciated that, similar to the above described manner, the thus occurring initiating shock is absorbed in a cup-shaped insert 25 so that the secondary charge 27 will not be ignited.

The fuse according to FIG. 5 at the head portion 2 thereof is provided with a threaded part 51 for screwing or threading into a body 52 indicated and outlined for a hand grenade. On axial bolt 3 secured to the head portion 2 there is journaled a yoke 4 which is secured in the rest position thereof by way of a pin 5 engaging in a pertaining bore. A preloaded spring plate 6 engages against the inner side of the yoke 4 thereby endeavoring to pivot the yoke around the axis defined by bolt 3 and to let go or release the same.

Further there is a spring 8 wound around the axis of the bolt 3 and the spring 8 has a shank or leg thereof engaging against the head portion 2 while a second shank or leg portion thereof abuts against a pivot arm 7 which likewise is journaled upon the axis of the bolt 3 and carries a hammer 9 which in turn engages against the spring plate 8 and yoke 4 therewith.

In the tubular-formed head portion 2 of the fuse there is inserted a detonator or ignition cap carrier 11 in which an ignition cap 10 is introduced centrically therewith. A cylindrical part 37 is connected with the ignition cap carrier 11 and a heating set 39 is pressed into a cylindrical recess thereof. A tubular-formed detonator carrier 19 is connected with the part 37 by way of an annular or ring-formed melting member 18

and a screw pressure spring 21 is held between the upper edge of the carrier 19 and a flange of the part 37.

In the part 37 there is further provided a chamber 38 which is closed by a disc 44 fastened in the part 37 by way of flange means or edge fastening. This disc 44 serves for pivotal journaling of a striker 43 which projects into the chamber 38 with a head part 41 provided with an ignition set 40. Additionally, the striker is held with a base or foot portion 45 in complementary fit in a recess 46 of the detonator carrier 19. Finally, the striker 43 is provided with an ignition passage 42 which is closed in the base or foot portion 45 by way of a flap valve 17. The flap valve 17 is flanged on one side in the base or foot portion 45. Between the base or bottom of the recess 46 and the face side of the foot part 45 there is provided a buffer 47 for damping shock or impact. A detonator cap 22 with detonator charge 23 screwed or threaded into the detonator carrier 19 projects into an intermediate housing chamber 23'' of the fuse housing 1. At the end of this fuse housing 1, there is threaded or screwed an insert 25 with a secondary valve 27.

The fuse according to FIG. 6 provides the same construction as the fuse according to FIG. 5 except for the illustrated detail. This detail consists therein that in the recess 38 of the part 37 there is secured a sleeve 49 with a pot-formed igniter set 48 into which a head portion 50 of the striker 43 projects without engagement during arresting of the striker 43. The embodiment and arrangement of disc 44, ignition passage 42 and flap valve 17 have already been described for the corresponding parts in FIG. 5.

Function of the percussion fuse of FIG. 6

If the released striker 43 encounters a shock or impact, then the head portion 50 thereof strikes against the igniter set 48. The ignition stream of the igniter set 48 passes through the ignition passage 42 and bends open the flap valve 17 in order to ignite the detonator cap illustrated in FIG. 5. The further occurring functions of the fuse then correspond to the functions described for FIG. 5.

It is, of course, to be understood that the present invention is, by no means, limited to the particular showing in the drawings but also comprises any modifications within the scope of the appended claims.

What is claimed is:

1. In a fuse structure for an explosive device: a tubular housing having a first ignitable charge at one end operable when ignited to detonate the explosive device, a detonator member in said housing having a first position remote from said first charge and a second position adjacent said first charge, said member carrying a second ignitable charge operable when ignited to ignite said first charge only when said detonator member is in the said second position thereof, biasing means urging said detonator member toward the said second position thereof, a retainer in said housing engaging said detonator member and holding it in said first position thereof and releasing said detonator member in response to ignition of said second charge, a third charge in said housing near the end of said housing opposite said first charge, an igniter cap on said housing operatively disposed adjacent said third charge for igniting said third charge when actuated, said third charge being operable when ignited to influence said

retainer and release said detonator member to move to said second position thereof, valve means on the side of said second charge facing away from said third charge, said valve means being held closed by said detonator member when the latter is in the said first position thereof and being released when said detonator member moves away from the said first position toward the said second position thereof, and means on the opposite side of said valve means from said second charge operable for igniting said second charge only when said valve means is released.

2. A fuse structure according to claim 1 in which said third charge is a delayed action rod-like charge and has one end near said igniter cap to be ignited thereby and the other end near the side of said valve means opposite said second charge and provides the said means to ignite said second charge when said valve means is released.

3. A fuse structure according to claim 1 in which said valve means comprises a flap valve which is clamped in closed position by said detonator member in the said fist position thereof.

4. A fuse structure according to claim 1 in which said valve means comprises a disc having a bendable flap element therein, and a clamp ring for holding said flap element in closed position and disposed between said flap element and said detonator member so as to release said flap element only when said detonator member moves away from its said fist position.

5. A fuse structure according to claim 1 which includes a cup-like element on the side of said first charge facing said detonator member and opening toward said detonator member so as to receive the end of said detonator member when the latter moves into its said second position, the side of said element facing said first charge having a central conical recess and said element being operable to transmit igniting shock to said first charge only when the end of the detonator member is disposed in said element.

6. A fuse structure according to claim 5 in which said detonator member is tubular and is formed of material which will not break when the said second charge is ignited, said detonator member having an outside diameter slidably fitting in said housing while the end part of said detonator member facing said first charge has a diameter receivable in the open side of said cup-shaped element.

7. A fuse structure according to claim 1 which in-

cludes a choke between said igniter cap and said third charge.

8. A fuse structure according to claim 2 which includes a choke between said third charge and said second charge.

9. A fuse structure according to claim 1 in which said means for igniting said second charge comprises a fourth charge on the side of said valve means opposite said second charge and adapted to become ignited upon impact, support means in said housing supporting said fourth charge and engaged by said detonator member in said first position thereof so as to be held against movement in said housing while being released for movement in said housing when said detonator member moves from said first position thereof to said second position thereof, said support means being movably connected to said housing for movement of said fourth charge into impacting engagement with said housing upon impacting of said explosive device against a surface.

10. A fuse structure according to claim 9 in which said support means has one end facing said detonator member and the said fourth charge mounted on the other end thereof and a passage extending through said support means from end to end thereof.

11. A fuse structure according to claim 1 in which said biasing means comprises a coil spring acting between said housing and said detonator member.

12. A fuse structure according to claim 1 in which said retainer is a heat softenable element.

13. A fuse structure according to claim 1 in which said means for igniting said second charge comprises a fourth charge on the side of said valve means opposite said second charge and adapted to become ignited upon impact, said fourth charge being stationarily supported in said housing, a member adapted to impact said fourth charge and engaged by said detonator member in said first position thereof so as to be held against movement in said housing while being released for movement in said housing when said detonator member moves from said first position thereof to said second position thereof, said member being movably connected to said housing so as to impact against said fourth charge when said explosive device impacts against a surface, and a passage extending through said member from said fourth charge to the side of said valve means opposite said second charge.
